UNITED STATES PATENT OFFICE

HAROLD KENNETH WHITEHORN, OF MAIDSTONE, ENGLAND

ELECTRIC RAILWAY SYSTEM

Application filed October 29, 1931, Serial No. 571,882, and in Great Britain October 30, 1930.

The object of this invention is to provide a means of transport which eliminates the risks attendant on relying on flanged wheels and also to provide a type of car or carriage which presents a symmetrical surface which ever way round it meets the medium (possibly rarefied) through which the car moves and also to minimize rolling tractive resistance.

10 The invention consists in a car of spherical exterior, hereinafter called a sphericar rolling so that it has contact at only one or two points such as either rolling in a tube rather larger in diameter than the sphericar or rolling on two railway lines either in open air or enclosed in a tube, and being propelled by the attraction towards the centres of a series of solenoids or electro-magnetic coils (excited by direct current) through which the sphericar passes; the current in the solenoids being cut off (in a manner to be described) at a time approximately when the sphericar occupies a central position in any one solenoid.

20 The current in the solenoid may be controlled by an "on" and "off" contactor actuated by "make" and "break" contacts or search coils touched or influenced by the sphericar on nearing the solenoid so that direct current is passed into the solenoid for sufficient time 30 to attract the sphericar towards the centre of the solenoid, the current being switched off when the sphericar is approximately central in the solenoid. The sphericar is thereby attracted and continues its journey, after the 35 solenoid current is switched off, towards the next solenoid placed approximately coaxial. Two railway lines may be the track on which the sphericar runs, banked where necessary, such track passing through the solenoids; or the track may be in a tube passing through the solenoids.

40 The invention will now be described by way of example with reference to the accompanying diagrammatic drawing in which

45 Figure 1 is a perspective view showing a form of the invention wherein two rear wheel lines pass through the solenoid.

50 Figure 2 is a view in elevation, partly in section, showing the points of contact between the sphericar and the rails.

Figure 3 is a perspective view showing the sphericar traveling in a tube arranged with in the solenoid.

55 Figure 4 is a view in section, partly in elevation, showing the point of contact between the sphericar and tube.

Figure 5 is a sectional view of a modified form of sphericar.

60 Fig. 1 represents a system of employing two railway lines passing through the solenoid, in which case there are two points of contact (see Fig. 2) between the sphericar 1, and the running rails 2, 2; the solenoid being indicated at 3, the "make" contact at 4, and the "break" contact at 5.

65 In Fig. 3 is shown a system in which the sphericar travels in a tube 6, and the solenoid 3 surrounds the tube. The tube is constructed with joints in any known manner near the solenoid to assist in assembly of the complete 70 system. A wound and insulated solenoid, the joints in the tube giving minimum mechanical interference to the smooth interior of the tube; the sphericar is shown dotted at 1 while Fig. 4 indicates that there is only one point of 75 contact between sphericar and tube giving very lowest tractive resistance; and air resistance may be lessened if the air in the tube is rarefied by partial vacuum created by external exhausting apparatus.

80 The tube may rest on ground level or be supported on a raised frame-work over roads or land and the tube may form part of a tubular bridge in crossing the country. The track, either as rails or tube, is preferably kept as 85 level and straight as possible. A system with one running rail and side check rails or a top check rail may be employed.

90 For propulsion the electric current to the solenoids is "direct" (not "alternating") but alternating current may be used for switching or for braking only. In the case of a tube the surface should have openings or slots or slits when alternating current is used in the solenoids for braking in order to minimize eddy currents in the tube; such openings also reduce the air resistance. The number of solenoids required for satisfactory progression will depend on the acceleration and speed required; as an example of a small toy 95

model on a four foot diameter track only two solenoids placed diametrically opposite and each one inch axial length were sufficient for satisfactory propulsion so in this instance the 5 ratio of solenoid length to track length was approximately one in seventy-five. In a full-sized system the length of the solenoid will be determined by first the speed of approach of the sphericar towards that particular sole- 10 noid, secondly, the inductance of the solenoid and the rate at which the current increases to its predetermined required value, thirdly, the rate at which the current is broken after the sphericar has been given its pro- 15 pelling impulse combined with the predetermined value of the current at the time the sphericar leaves the end of the solenoid.

An alternative method of timing the operation of the contactors which control the current to the solenoids is to employ a weak current in the solenoid shortly before it has to be used for propulsion (possibly timed from a previously active solenoid) so that the approaching sphericar enters the weak magnetic field so produced which will have the effect of inductively altering the value of the weak current in the solenoid, and such alteration of current can be used to operate a relay or thermionic circuit which in turn 20 leads to actuation of the main contactor for that solenoid. Thermionic means may also be employed to actuate a relay for a contactor in breaking the coil current at the correct instant, but illustration is not considered 25 necessary in view of the fact that such arrangements and the actual connections can be readily devised by those skilled in the art.

In the case of a small toy railway such as the four-foot diameter one mentioned above 30 with about one inch model railway lines the solenoids have been operated by hand-switching and time-judged as the sphericar (or an iron ball in this case) approaches, the solenoid current being suddenly switched off 35 when the small sphericar is approximately central in the solenoid; such a toy could be used in fairs and amusement places and skill exercised in trying to throw the sphericar (by action of the solenoids) off the track, 40 and possibly there might be added amusement by numbered receptacles into which the sphericar could be aimed.

The construction of the sphericar will depend on the use for which it is intended. 45 When needed for conveyance of goods such as mails and other articles which will not be hurt by alteration of position, the sphericar may be a plain shell of iron, steel or other magnetic material or partly magneto by portions of iron or magnetic material embedded 50 in a lighter metal shell; a trap-door being provided to permit putting in and taking out the goods carried when the purpose is animal or passenger transit or conveyance of goods 55 which may not be turned upside down, then

one or more shells are needed placed approximately concentrically 7, 8, 9 (see Fig. 5), the outer one 7 being wholly or partly magnetic as described above and the inner ones floating in oil or fluid or mercury 10 so that the inmost shall be capable of riding always upright and this inner shell 9 can be provided with permanent ballast to weight down the bottom part. Such ballast can also form the floor 11 of the sphericar, and beneath the floor may be 75 fitted two gyroscope wheels 12, revolving in opposite directions and driven by one or more electric motors 13 supplied by accumulators 14 in the bottom of the car; the gyroscopes 80 preferably run in vacuum to reduce air friction losses.

After the sphericar has attained the maximum speed required and is nearing its destination, the remainder of the journey can be effected by coasting through slotted tubes, 85 and as the sphericar nears its destination the slots 15 would be less frequent so that a gentle air-cushioning effect brings the car to rest; the last stage being in tube without slots 90 so that air-compression stops the car. The solenoids over the stopping or coasting section would be cut out of circuit for any one journey. Stopping may be effected by applying alternating or direct magnetic flux 95 acting on the outer shell in a solenoid of considerable length without any cut-out to assist in propulsion; such stopping would be in the form of an eddy current braking action. The sphericar might obviously carry rings of 100 copper or other electrical conductor embedded in its surface and possibly overlapping, so that eddy effects would be appreciable when required.

The control of the line for any one direction can be electrically operated from a single point. Normal telegraphy with other electric operation can be incorporated. It is estimated that the journey from London to Glasgow would take 44 minutes, limited by the maximum rate of acceleration which the 110 human heart can stand according to present knowledge.

I claim:—

1. In an electric transport system the combination of a track, a spherical body, running thereon, and direct-current electro-magnetic coils spaced along the track and energized to accelerate the said body along the said track.

2. In an electric transport system the combination of a track, a spherical body running thereon, and direct-current electro-magnetic coils spaced along the track so as to be traversed in turn by said body and means to energize said coils in turn on the approach of the said body to accelerate the said body along the said track.

3. In an electric transport system the combination of a tubular track, a spherical body running thereon, and direct-current electro-

magnetic coils spaced along the track and energized to accelerate the said body along the said track.

4. In an electric transport system the combination of a track, a spherical body running thereon, and direct-current electro-magnetic coils spaced along the track with contactor control means for the supply of current to said coils.

5. In an electric transport system the combination of a track, a spherical body running thereon, and direct-current electro-magnetic coils spaced along the track with contactor control means for the supply of current to said coils the arrangement being such as to cause the said body to actuate the said control means as it reaches predetermined positions relatively to the said coils.

6. A car of spherical exterior in combination with a slotted tube forming a track, coils surrounding said track at predetermined intervals, and switching means for said coils.

In testimony whereof I have signed my name to this specification.

HAROLD KENNETH WHITEHORN.
